CHILDREN'S WHEELED TOY

Milton D. Sacks, New York, N. Y.

Application December 21, 1949, Serial No. 134,203

2 Claims. (Cl. 46—204)

1

This invention relates to children's wheeled toys, and more particularly to a type which will cause an object, such as a ball, to be tossed back and forth through a guided path as the toy is pulled or otherwise propelled across the floor or other surface.

An object of the invention is to provide a toy of this character which will be of simple and inexpensive construction; which will operate smoothly, and will be constructed to withstand considerable use and abuse by the child.

More particularly, the invention contemplates the provision of a base supported on freely-movable wheels, the base being provided with an upwardly extending curved rod on which a ball or other object is slideable, the wheels of the vehicle being provided with laterally extending resilient impellers, one or the other of which engages the ball in a manner to cause it to be tossed or propelled from one end of the curved rod to the other. The result of this arrangement is that on the continuous forward movement of the vehicle, the ball is tossed or propelled back and forth in a reciprocating manner on the guide rod on the top of the toy and in a manner to amuse and interest the child engaged in pulling the toy.

These and other objects are attained by the invention, a more particular description of which will hereinafter appear and be set forth in the claims appended hereto.

In the accompanying drawing, wherein an illustrative embodiment of the invention is disclosed, Fig. 1 is a top plan view of the toy constructed in accordance with the invention; Fig. 2 is a side elevation of the same, with one of the wheels fragmentarily shown and the ball being shown in section and in an intermediate position; Fig. 3 is a front elevation of the toy, with a portion of the same shown in section, and Fig. 4 is a perspective view of a portion of one of the wheels, showing one of the ball-impellers thereon.

Referring to the drawing, 1 indicates the base or platform of the toy vehicle, the same being supported by four wheels, the front wheels being shown at 2 and 3 and the rear wheels at 5 and 6. Axles 4 support the front wheels, which rotate freely thereon, and similar axles 7 support the freely-rotatable rear wheels. These axles are attached to the platform or base 1 in any suitable manner.

Secured to and arising from the top of the base 1 is a curved rod or wire loop 8, which has its forward end 9 embedded in the base or platform 1 adjacent to the front wheel 3, and its rear end 10 similarly embedded in the base 1 near the rear

2

wheel 5. The loop 8 thus extends angularly across the top of the base 1 and slidably mounted on the loop is a ball 11. Said ball, which is preferably of lightweight, celluloid construction, is provided with the aperture 12 through which the rod or loop 8 passes. The ball 11 is thus so mounted on the loop 8 that it may be freely slid back and forth thereon, which operation is caused to be performed by projections on the wheels 3 and 5 as the vehicle is moved forwardly over the floor or other supporting surface. As a substitute for the ball, some other ornamental article or object might be used.

Secured to and extending laterally from the inner side of the front wheel 3 is the front impeller-finger 15 which operates to engage against and under the ball when the ball is located at the front end 9 of the loop, to thereby raise and toss the ball rearwardly along the loop to its rear position. The impeller-finger 15 consists of a loop-shaped member of thin, flat and highly-flexible spring metal so that it is very resilient and can be flexed, in the manner to be described, to exert a snapping action against the ball to elevate and shift it rearwardly along the guide loop 8. Located on the under side of the base or platform 1 is an inclined surface 16, and as the wheel 3 is rotated, the finger 15 will engage against such inclined surface 16 and will be flexed as seen in Fig. 3. As the wheel continues its rotation, the finger 15 will be sprung past the edge of the platform with a spring or snap action, and it will engage against and pass under the ball 11, tossing it upwardly and along the loop 8 until it reaches the rear end of the loop and rests upon the platform at that location.

Provided on the rear wheel 5 is an impeller-finger 13 which is similar in construction to the finger 15 on the front wheel 3. The rear finger 13 engages behind the ball 11 as the toy is moved forwardly, to thus toss the ball upwardly and along the loop 8 to its forward position thereon in readiness for engagement by the front finger 15. A notch 14 is provided in the edge of the base or platform to permit the passage of the finger 13 as the finger passes downwardly in the rotation of the wheel 5.

From the foregoing, the operation of the toy will be readily understood. It may be moved along the floor or other surface by being pulled by the string 17, or it might be pushed from behind by a rod or rearward extension from the platform 1. Assuring that the ball 11 is located at the rear end 10 of the curved rod 8, as shown in Fig. 1, it will be clear that as the rear wheel

5 is rotated, the impeller-finger 13 thereon will be brought up behind and then moved under the ball 11, striking the curved face thereof and causing the ball to be tossed upwardly and along the rod 8 to reach and rest upon the front part of the platform 1 at the forward end 9 of the rod 8. After the impeller-finger 13 on the rear wheel passes below the ball and tosses the same as above described, the finger then moves downwardly through the notch 14.

As the front wheel 3 is rotated by the forward movement of the vehicle across the floor, the impeller-finger 15 on said wheel comes into contact with the inclined surface 16 on the under side of the platform 1, the finger being flexed thereby as it is moved across said surface, as clearly shown in dotted lines in Fig. 3. The finger 15 next moves past said surface 16 and springs smartly against and under the ball 11 which at this time is at the front end of the curved rod or loop 8, and as it snaps against and under the ball 11, it will act to toss the ball upwardly and along the rod 8, causing the ball to slide along the rod to the rear end of the same to the position shown in Fig. 1. The ball is next tossed upwardly and forwardly by the rear-impeller finger 13 to repeat the cycle described.

In the forward movement of the vehicle across a floor or other support, all of the wheels of the vehicle are rotated in the same direction, while the ball is tossed back and forth or reciprocated. The effect secured is interesting and amusing to the child and the device operates smoothly as it is moved across the floor.

The impeller-fingers 13 and 15 are made of extremely flexible and springy material and thus are not readily damaged. If the device is moved backwardly, the front finger 15 will, due to its extreme flexibility, readily spring past the edge of the platform 1 without damage to the finger.

Having described one embodiment of the invention, it is obvious that the same is not to be restricted thereto, but is broad enough to cover all structures coming within the scope of the annexed claims.

What I claim is:

1. A toy consisting of a vehicle having a platform supported by wheels, a wire loop attached at the top of the platform and arising from the same in arcuate fashion, one end of the loop being situated near one of the rear wheels and the other end of the loop being situated near one of the front wheels, a ball slideable on the loop from one end of the loop to the other, said ball normally resting on the platform at either end of the loop, one of the front wheels being provided with an inwardly-extending spring impeller-finger, means on the platform adjacent said finger for causing flexure of the finger by engagement of

the same with said means whereby said finger, when moving away from said means, will snap against the ball and toss the same upwardly and along the loop to the rear end of the loop, and means on one of the rear wheels for then engaging the ball and tossing it to cause it to move along the loop to the front end of the loop, all of the wheels of the vehicle being rotated in the same direction as the vehicle is moved forwardly over a supporting surface, and the tossing of the ball occurring during such forward movement of the vehicle.

2. A toy comprising a vehicle having a platform mounted between a pair of front wheels and a pair of rear wheels, a wire loop fixed in the platform and extending upwardly on a curve therefrom, the front end of the loop being located near one of the front wheels and the rear end of the loop being located near one of the rear wheels, a ball slideable on the loop and normally positioned at either the front or rear end of the loop, one of the front wheels being provided with a laterally extending resilient finger for direct contact with the ball when it is at the front end of the loop to thereby toss the ball and cause it to slide along the loop to the rear end of the loop, one of the rear wheels being also provided with a laterally-extending resilient finger for direct contact with the ball when the ball is at the rear end of the loop to thereby toss the ball and cause it to slide along the loop to the front end of the loop, said back and forward movement of the ball occurring while both the front and rear wheels of the vehicle are rotating in the same direction as the vehicle progresses forwardly over a supporting surface, each of the resilient fingers being in the form of a springy loop extending from the inside of the wheels, the platform being provided with a notch near one of the rear wheels to permit the passage of the finger on said wheel as the wheel is rotated, and an inclined surface on the under side of the platform near the front wheel, said surface engaging the finger on said wheel to thereby flex the finger as said finger is moved over said inclined surface preparatory to striking the ball at the forward end of the loop.
